(57) **CLAIM**

The ornamental design for a handlebar for cycles or motorcycles, as shown and described.

DESCRIPTION

1.1 is a front perspective view of a handlebar for cycles or motorcycles embodying my new design;

1.2 is a rear perspective view thereof;

1.3 is a top plan view thereof;

1.4 is a front elevation view thereof;

1.5 is a rear elevation view thereof;

1.6 is a bottom plan view thereof;

1.7 is a right side elevation view thereof; and;

1.8 is a left side elevation view thereof.

The broken lines in the Figures show portions of the handlebar which form no part of the claimed design.

1 Claim, 4 Drawing Sheets
